OR D 13,019

DESIGN FOR A HEATING-STOVE.

Design No. 13,019, dated July 4, 1882.

UNITED STATES PATENT OFFICE.

EDGAR W. ANTHONY, OF BOSTON, MASSACHUSETTS.

DESIGN FOR A HEATING-STOVE.

SPECIFICATION forming part of Design No. 13,019, dated July 4, 1882.

Application filed April 3, 1882. Term of patent 14 years.

To all whom it may concern:

Be it known that I, EDGAR W. ANTHONY, of Boston, in the county of Suffolk and State of Massachusetts, a citizen of the United States, have made a certain new and useful Design for Stoves, of which the following is a full, clear, and exact description, reference being had to the accompanying photograph, forming a part of this specification, to which reference is made in explaining its nature.

The general features of the design are represented in the accompanying photograph, and embrace, besides the general form and proportion of the stove as a whole, the especial form and ornamentation of the legs, base portion, rail, body, upper door and frame, top plate, and urn. The stove as a whole embraces a base, A, which is, with the exception of the rounded flue portion at the rear, substantially rectangular in shape and wider on the front than it is deep, and is made of cast metal; also, a body, B, which is oval in cross-section, made of sheet metal, relieved by the lines of corrugations, and having upon its front an ornamental plate, b', and door b², and the top plate and cover, C, which are also oval in horizontal section, and are inclined from near the center of the cover to the edge of the plate, as represented, the cover being surmounted by an urn, D, if desired. These features should have generally the shape and proportion shown by the photograph; but the specific ornamentation may be modified and changed as desired. The rear pipe, containing the down and up take passages, I do not consider as an especial feature of the design.

The special design for the stove-leg embraces the curved foot portion e, the plain section e', and the upper section, e², ornamented by figures and scroll-work. The base A comprises the lower base-plate, a, the upper base-plate, a', and front and end sections, a² a³. As stated, this portion of the stove is rectangular, and is wider than it is deep. The greater portion of the front is taken by the ash-pit door a⁴, which has rounded corners and oval damper-holes and is ornamented by figures and lines, as shown in the photograph. The front plate, to which the door is hinged, is plain, except the upper portion, a⁵. Each corner of the base has the two pillars a⁶ a⁷, which are

alike in every detail, except that one is upon the front or back and the other is upon the end of the stove. Each pillar has a separate ornamental pedestal or base and rounded or cut-away corners and front ornamentation, as represented. Between the pillars, and forming the corner of the base, is the plain, rounded, or curved column, a⁸, the base and top of which correspond in ornamentation to the base and top of the pillars. Between the side pillars of the stove is the plate or panel a⁹, all shown in the photograph, and the lower and upper ornamental portions, a¹⁰ a¹¹, which follow the shape of the corresponding parts of the pillars.

The body B preferably has three lines of raised beads or moldings, b³, about its lower section, three lines, b⁴, about its central section, one line, b⁵, about its upper section, and the lines b⁶ at its top.

The features of the door-plate b' are so well shown by the photograph that further description of them is unnecessary.

The shape and ornamentation of the door b² is also well represented by the photograph. It may have a mica light, if desired.

The top plate and cover, C, are oval, and slant from the top e of the cover to the edge of the plate. This inclined part has three lines of ornamentation, c' c² c³, which are separated by the two sections c⁴ c⁵ of plain molding or undulations.

The name-plate F, shaped and ornamented as shown, may be fastened to the front of the top plate, if desired. Immediately below the top plate there may be arranged the open-work band G. The shape and ornamentation of the urn D and its supports are well illustrated by the photograph.

The rail H is somewhat above the base portion, and comprises the front section, h', which is curved in cross-section, has a plain top, and outer and downwardly extending section ornamented by alternate projections and recesses, 95 as shown, and the side sections, h', which extend from the front section near either end backwardly, are straight upon their outer edge, with the exception of projections h², and at their juncture with the top rail are spread or extended inwardly. The upper surface of the side rail may be ornamented with sero"

work, and the upper surface of the upper base-plate, a' , may be also ornamented, if desired.

The edges of the two base-plates and of the top plate may be polished.

5 Having thus fully described my invention, I claim and desire to secure by Letters Patent of the United States—

1. The design for heating-stove shown and described.

10 2. The design for a stove-leg shown and described.

3. The design for a stove-base shown and described.

4. The design for ash-pit door shown and described.

15 5. The design for the body of a heating-stove shown and described.

6. The design for a stove, comprising the pillars a^6 a^7 , ornamented as shown.

7. The design for combustion-chamber door 20 shown and described.

8. The design for door-plate shown and described.

9. The design for cover and top plate shown and described.

10. The design for stove-urn shown and described.

11. The design for stove-rail shown and described.

12. The design for corner ornamentation of 30 a stove, the pillars a^6 a^7 having straight edge lines and ornamentation, as shown, and a rounded corner, a^8 , between the pillars, all as shown and described.

EDGAR W. ANTHONY.
